UNITED STATES PATENT OFFICE.

JENS BLINKILDE, OF DETROIT, MICHIGAN.

VALVE GRINDER.

1,408,254.

Specification of Letters Patent. Patented Feb. 28, 1922.

Application filed March 15, 1920. Serial No. 365,817.

To all whom it may concern:

Be it known that I, JENS BLINKILDE, a citizen of the United States of America, residing at Detroit, in the county of Wayne and State of Michigan, have invented certain new and useful Improvements in Valve Grinders, of which the following is a specification, reference being had therein to the accompanying drawings.

10 This invention relates to devices for use in grinding valves of internal combustion engines to their seats and its object is to facilitate the operation and increase the accuracy of the work, and, further, to provide a machine for the purpose which is cheap to manufacture and may be quickly and easily applied to the work and operated by an unskilled person. It is also an object, to provide a machine which may be readily 20 adjusted for operation upon various makes of engines and which will afford a yielding pressure upon the valve operated upon to hold the same to its seat and is arranged to provide for variations in valve and seat and 25 exert an even pressure thereon. A further object is to provide the machine with simple and efficient means for rotating the valve and to also provide certain other new and useful features in the construction, arrangement and combination of parts, all as hereinafter more fully described.

With the above and other ends in view, the invention consists in the matters herein-after set forth and more particularly set 35 forth in the appended claims reference being had to the accompanying drawing, in which—

Figure 1 is a side elevation of a machine illustrative of the invention;

40 Fig. 2 a perspective view of the same, illustrating the application of the same in use; and

Fig. 3 is a detail of a frame joint.

In the operation of internal combustion engines, it is found that after a period of service it becomes necessary to grind these valves to their seats to prevent leakage due to wear and fitting of the contact surfaces, and this grinding is accomplished by placing 45 a small amount of grinding material upon the valve seat and then turning the valve in contact with its seat under pressure. In order to make a perfect seat in such operation, it is necessary that the valve be firmly 50 and evenly held with an even pressure toward its seat and turned while so held. It

is a difficult operation, requiring skill to so hold and turn the valve that a good seat will be formed and the operation is slow.

With the use of the machine embodying the present invention, the valve is securely held and pressed upon its seat with a constant even pressure which is not modified by the turning operation and the valve is always free to tilt slightly and conform to its seat, thus making a perfect grinding operation without great attention or skill on the part of the operator.

As illustrated in the drawing, the machine comprises a base 1 which is formed with a longitudinal slot 2 to receive a bolt or bolts 3 by means of which the base is securely held down upon the flat upper surface 4 of a cylinder block 5, in which upper surface, the seats for the valves 6 are formed, said bolts 7 being engaged with any of the usual openings in the face of the cylinder block. From the rear end portion of the base 1 rises a post 7 preferably formed integral with the base, and attached to the upper end of the post is a yoke arm 8 carrying an adjustable bracket 9 at its free end, which bracket is provided with alined bearings 10 for a vertical shaft 11 which is free to turn therein. On this shaft below the bracket, is secured 85 a pulley 12 and between said pulley and the lower of the bearings 10 is sleeved upon the shaft, a coiled spring 13 which normally exerts a force tending to hold the shaft removed endwise in its bearings with a head 90 14 on the upper end of the shaft in contact with the upper of said bearings. To the lower end of the shaft is attached a block 15 by means of a transverse pivot pin 16 and the lower end of this block has a transverse 95 slot to receive a pair of fingers 17 which are pivotally attached to the block and pivotally connected by means of a pivot pin 18 extending transversely of the block in a direction at right angles to the pivot 16 and 100 through openings in the overlapped ends of the finger 17. At their free ends, these fingers are formed to engage openings in the valves 6 usually provided for the engagement of a tool by means of which they may 105 be turned while seated in their seats for the purpose of grinding the valves to their seats.

By reason of the pivotal connection between said fingers 17, they may be swung 110 toward or from each other to engage holes of varying distances apart in the valves of

different makes of motors, and by reason of the double pivotal connection of these fingers to the shaft by the pivots 16 and 18 extending transversely of the shaft and 5 block at right angles to each other a universal connection of the fingers to the shaft is afforded so that when the fingers are engaged with a valve, the valve and shaft will be free to tilt or move relatively in a 10 lateral direction, thus providing for slight inaccuracies in the valve and seat and in the alinement of the shaft with the valve axis. Further, by the pivotal attachment of the fingers to the block, said fingers may be 15 detached and a turning tool of another form substituted therefor, as when the valves are provided with a slot or other means instead of holes.

The spring 13 exerts a constant force to 20 hold the fingers engaged with the holes in the valve and to put a pressure upon the valve to hold it into its seat, and to vary the tension of the spring, the bracket 9 is adjustably attached to the arm 8 by means of 25 bolts 19 passing through a vertical slot 20 in the bracket and engaging openings in the arm, said slot extending parallel to the longitudinal axis of the shaft 11, and in order that the fingers 17 may be readily engaged 30 with or disengaged from the valve, the arm 8 is pivotally attached to the upper end of the post 7 by means of a transverse pivot bolt 21, thus permitting said arm to be 35 swung upwardly to lift the fingers out of engagement with the work and so that the valve may be readily lifted from its seat from time to time during the grinding operation for the purpose of examination of the 40 valve and its seat. To hold the arm 8 in its lowered or operative position with the shaft 11 in perfect vertical relation to the base 1, and consequently in proper relation to the 45 valve to be ground, the pivoted end of said arm is forked to embrace the upper end of the post, the pivot bolt 21 passing through 50 openings in the arms 22 of this forked end and through an opening in the interposed end of the post, and adjacent the lower ends of these arms 22, they are each formed with a slot 23 extending inward from one edge 55 of the arm to receive a screw bolt 24 extending through the slots and an opening in the post and provided with a thumb nut 25, said slots being curved concentrically with the axis of the pivotal attachment of the arm to the post. These slots are also of such a length as to limit the downward turning 60 movement of the arm.

To rotate the shaft 11 and thus turn the 65 valve with which the fingers 17 are engaged, a flexible belt, cord or cable 26 is given a single wrap or turn around the pulley 12 and one end thereof made fast to a coiled spring 27, the opposite end of which is attached in any suitable manner to the post 7.

By grasping the free end of the cord 26 as illustrated in Fig. 2, and pulling thereon, the operator causes a rotation of the pulley and shaft in one direction, and by letting up on the cord, the spring having been put 70 under tension, will exert a force to rotate the shaft in a reverse direction. Very simple and efficient means are thus provided for rotating the shaft to turn the valve back and forth on its seat, and the operation of this 75 turning means will have no tendency to tilt the valve on its seat and will not interfere with the steady constant pressure exerted by the spring 13 upon the valve to hold it 80 against its seat, evenly during its rotation.

By employing a suitable holding frame which is illustrated as comprising the base 1, post 7 and arm 8, the means carried thereby for engaging and turning the engine valve is rigidly held in proper vertical relation to the valve and its seat, as the base of the frame is arranged to be secured upon the upper flat surface of the engine block 5 and in all engines having a removable head, this surface forms a perfect seat for the frame. 85 When the machine is used upon other types of engine, the frame may be readily bolted upon any convenient flat surface or surfaces which are parallel with the plane of the valve seat and the tool or fingers 17 brought 90 into engagement with the valve, the movable bracket 9 providing for an adjustment of the shaft vertically.

Obviously, changes may be made within the scope of the appended claims without departing from the spirit of the invention, and I do not, therefore, limit myself to the construction or arrangement of parts shown.

What I claim is:—

1. In a device of the character described, 105 the combination of a supporting frame comprising a base, a post and an arm pivotally attached to the post, a vertical shaft mounted in bearings on the free end of the arm, means for turning the shaft, a tool for engaging and turning a valve, and a member connecting said tool and lower end of said shaft, said member being connected to said shaft by a transverse pivot and to said tool by a transverse pivot extending at right 110 angles to the other pivot.

2. In a device of the character described, 120 the combination of a supporting frame having a laterally extending arm, a bracket adjustably attached to said arm and provided with bearings, a shaft in said bearings free to rotate and move longitudinally therein, a pulley secured on the shaft, a tool pivotally attached to the lower end of the shaft by transverse pivots extending at right angles 125 to each other, a spring sleeved on the shaft between the bracket and pulley, a cord wrapped about the pulley, and a spring attached to one end of the cord at one end and at its opposite end to the frame.

3. In a device of the character described, the combination of a supporting frame comprising a longitudinally slotted base, a vertical post at one end of the base and a laterally extending arm pivotally attached to the upper end of the post, said pivotal connection of said arm to said post being formed to limit the turning movement of said arm, a bracket adjustably secured to the free end 10 of the arm and provided with bearings, a shaft in said bearings free to turn and to move longitudinally therein, a tool on the lower end of the shaft to engage a valve and

comprising a pair of pivoted fingers, a coiled spring sleeved on the shaft to move the same 15 longitudinally toward the valve, a pulley secured in the shaft, a cord wrapped about the pulley, and a spring connecting one end of the cord to the frame.

In testimony whereof I affix my signature 20 in the presence of two witnesses.

JENS BLINKILDE.
